UNITED STATES PATENT OFFICE.

CURTIS HUSSEY VEEDER, OF HARTFORD, CONNECTICUT, ASSIGNOR TO
THE VEEDER MANUFACTURING COMPANY, OF SAME PLACE.

DESIGN FOR A CASE FOR REGISTERS.

SPECIFICATION forming part of Design No. 28,077, dated December 21, 1897.

Application filed October 11, 1897. Serial No. 654,898. Term of patent 14 years.

To all whom it may concern:

- Be it known that I, CURTIS HUSSEY VEEDER, a citizen of the United States, residing in the city and county of Hartford, in the State of Connecticut, have invented a certain new and original Design for Cases for Registers, of which the following is a specification, reference being had to the accompanying drawings, forming a part hereof.
- 10 My invention relates to designs for cases or shells for cyclometers and other like instruments; and it consists in a case having the shape and configuration substantially as shown in the accompanying drawings, in which—
- 15 Figure 1 is a perspective view of a shell or case which embodies my design. Fig. 2 is a side view of the shell or case shown in Fig. 1, and Fig. 3 is a plan view thereof.
- 20 Referring to the drawings, it will be seen that in accordance with my design two generally or substantially cylindrical parts *a* and

b are united by a middle part *c*, the side lines *d* of which may be concaved slightly. When viewed from the side, the case presents the 25 appearance of an elongated body with rounded ends, and when viewed in plan is substantially rectangular, with two transverse parallel openings *e e*.

The leading features of my design may be 30 described as the substantially cylindrical parts, united by a middle part *c*, and the transverse parallel openings.

What I claim, and desire to secure by Letters Patent, is—

35 A design for a case for registers, substantially as shown and described.

This specification signed and witnessed this 8th day of October, A. D. 1897.

CURTIS HUSSEY VEEDER.

In presence of—

A. N. JESBERA,
F. M. EGGLESTON.
